[57] ABSTRACT

The bearings for the rotor of a crusher are positioned substantially in the end walls of a rotary drum concentrically surrounding the rotor, one of the bearings being mounted on a fixed support extending to an opening in one end wall, and the other bearing being mounted in the other end wall.

FIG.1

FIG.2

INVENTOR.
ROBERT LUCAS

BY *Kurt Kellman*

AGENT

CRUSHER

The present invention relates to improvements in crushers wherein a rotor is mounted for rotation about a horizontal axis, a plurality of radially extending crushing elements are on the rotor, and a rotary drum concentrically surrounds the rotor.

In known crushers of this type, the bearings for the rotor shaft are positioned outside the drum, which makes the shaft long and requires the rotary speed of the rotor to be limited for reasons of safety.

It is the primary object of this invention to overcome this disadvantage and to provide rotor bearings which are at least substantially in the planes of the end walls of the drum. This permits the rotor shaft to be relatively short and correspondingly to increase the speed of rotation thereof, which enhances the efficiency of the crushing operation.

The above and other objects and advantages are accomplished in accordance with the invention by providing a first bearing for the rotor positioned substantially in the plane of the one drum end wall in an opening in the wall, the one end wall defining inlet opening means for feeding material to be crushed into the interior of the drum and air for evacuating crushed material from the interior of the drum. A fixed support extends to the end wall opening and the first bearing is mounted on the fixed support. A second bearing for the rotor is mounted in the other end wall of the drum which is flat. The cylindrical wall of the drum defines outlet opening means for discharging the crushed material and the air.

The above and other features of the present invention will become more apparent in the following description of a now preferred embodiment, taken in conjunction with the accompanying drawing wherein

FIG. 1 is a longitudinal section of the crusher; and

FIG. 2 is a partial end view of the crusher, viewing the left end of FIG. 1, half of the figure showing a transverse cross section of the crusher.

Referring now to the drawing, there is seen a rotary drum 10 mounted for rotation about a horizontal axis and concentrically surrounding a rotor 12 disposed coaxially in the interior of the drum. A plurality of radially extending crushing elements illustrated as hammers 40 are mounted on the rotor, the hammers being pivotally supported on axially extending axles 42 which are carried by rotor 12. The rotor consists of shaft 38 to which are keyed a plurality of adjacent discs 36 whose hubs maintain annular guide channels between adjacent discs for guiding the hammers during their pivotal movement about axles 42.

The rotary drum 10 has a cylindrical wall 14 of sheet metal which is lined interiorly by protective plates 16 which have axially extending ribs 16a defining axially extending channels 24 therebetween.

An annular partition wall 18 divides the interior of the drum into a major crushing chamber and a minor discharge chamber. Regularly spaced outlet openings or ports 20 in the cylindrical drum wall 14 in the discharge chamber open into a fixed hood or casing 22 which surrounds this portion of the drum. The ribs 16 extend only through the crushing chamber of the drum, i.e. up to the partition wall 18.

A journal or trunnion 26 of large diameter is welded or otherwise suitably affixed to the cylindrical wall of the drum at one end thereof. The other end of the drum is closed by a bottom or end wall 28 of sheet metal which is similarly welded or otherwise affixed to the cylindrical drum wall. A tubular trunnion or journal 30 is bolted or otherwise suitably affixed to the bottom wall 28. The trunnions 26 and 30 are rotatably mounted on bearings 32 and 34, respectively.

One end of rotor shaft 38 is journaled in bearing 44 which is journaled in trunnion 30. The other end of the rotor shaft is journaled in bearing 46 affixed to a fixed gooseneck support 48 which extends to a recess or opening in the one end wall of the drum. A sheet metal web 50 affixed to the support 48 closes off the opening in the one end wall of the drum and extends to the trunnion 26.

A pair of feed funnels or channels 52, 52 are disposed on respective sides of the fixed support 48 to provide inlet opening means for introducing material to be crushed and evacuating air for the crushed material into the interior of the drum, registering openings in the sheet metal web 50 being provided for these funnels.

A pinion 54 is affixed to the tubular trunnion 30 so that the drum may be rotated by a chain drive (not shown) engaging the pinion. The rotor shaft is coupled to a suitable motor means (not shown) for rotation.

If desired, the bearing 32 may be replaced by rollers supporting the cylindrical drum wall and operated to rotate the drum. In this case, the roller bearings may have rubber linings or tires for frictional driving engagement with the cylindrical drum wall.

The crusher operates as follows:

The drum 10 and rotor 12 are rotated in the same or opposite directions. The material to be crushed and the evacuating air are introduced through feed funnels 52. In the interior 20 of the drum, the material is lifted by the axial channels 24 and falls back on the rotor 12 which turns at great speed. Thus, the material is subjected several times to the impact of the pivoting hammers in the crushing chamber. When the material has 25 attained a given degree of comminution, it is entrained by the evacuating air stream in the interior of the drum and discharged with the air through outlet ports 20 into the hood 22.

The dwell time of the material in the drum is controlled by the radius of the annular partition wall 18.

It is thus possible to extend the dwell time in the drum beyond that in conventional hammer mills, which permits the obtention of a larger proportion of finely milled or crushed material. Furthermore, the crusher of the present invention also reduces the wear on the hammers because it suppresses the crushing of the material by attrition between the hammers and the grill of conventional hammer mills.

When it is desired to use the crusher as a mill and drier, the 40 thermic exchange coefficient between the hot evacuating gas supplied to the drum and the material to be crushed is particularly high by virtue of the intense stirring which the channels 24 and the rotor 12 impose upon the material during its treatment in the drum. In this case, the bearing 46 of the rotor 45 which is situated near the entrance of the hot gas is lubricated and cooled by circulating oil or an air current suitably introduced into the interior of support 48.

The crusher of this invention is particularly useful for crushing and drying products before they are finally milled, thus 50 reducing the power requirements of the final mill.

I claim:

1. In a crusher having a rotor mounted on two axially spaced bearings about a horizontal axis, a plurality of radially extending crushing elements on the rotor, and a rotary drum concentrically surrounding the rotor, the drum consisting of a cylindrical wall and two end walls, one of the end walls defining inlet opening means for feeding material to be crushed into the interior of the drum and air for evacuating crushed material from the interior of the drum, the improvement which comprises:
  - a. a trunnion of large diameter at said one end wall of the drum,
  - b. a first one of the rotor bearings positioned substantially in the plane of the one drum end wall,
    1. the first bearing being concentric with the trunnion and defining therewith an annular opening of large diameter to form the inlet opening means, and
    - c. a fixed support outside and independent of the drum and extending into the end wall opening,
      1. the first bearing being mounted on the fixed support.
      2. In the crusher of claim 1, rollers supporting the drum at said one end wall.
      3. In the crusher of claim 1, wherein the fixed support is of gooseneck shape.

4. In the crusher of claim 1, wherein a closure wall is affixed to the fixed support for partially closing the annular opening, and further comprising at least one feed channel registering with openings in the closure for feeding the material into the interior of the drum.

5. In the crusher of claim 1, wherein the second one of the rotor bearings is mounted in the other end wall of the drum and includes a tubular trunnion on the other end wall, a fixed bearing supporting the tubular trunnion, and a rotor bearing journaled in the tubular trunnion.

6. In the crusher of claim 5, an annular partition dividing the interior of the drum into a major crushing chamber and a minor discharge chamber, and the cylindrical wall of the drum defining outlet opening means in the discharge chamber for discharging the crushed material and the air.

7. In the crusher of claim 1, protective plates lining the cylindrical wall of the drum and axially extending ribs on the plates defining axially extending channels therebetween.
